UNITED STATES PATENT OFFICE

ROBERT O. FERGUSON, OF BRISTOL, TENNESSEE

ALARM CLOCK

Application filed July 28, 1931. Serial No. 553,630.

This invention relates to alarm clocks and more particularly to certain improvements in alarm clocks whereby they are capable of acting as fire signals.

5 An important feature of the invention is comprised in an improved mechanism for sounding an alarm which, while ordinarily time-actuated, may be actuated through the fusing of a controlling element upon an ab-
 10 normal rise of temperature, and without in-
terference with the time-actuated means of the alarm. The mechanism referred to em-
bodies two slidable members which are caused to separate upon the occurrence of a fire,
 15 through spring tension devices, and to re-
lease certain devices which normally prevent the operation of the alarm until the time mechanism of the clock acts to release such devices. Upon movement of such members
 20 the hammer or striker of the gong is released if the usual restraining stop happens to be in obstructing position, and at the same time the usual pallet wheel is simultaneously freed from the time controlled detent which
 25 ordinarily prevents its movement, and these two functions are performed without inter-
fering with the ordinary adjustments which are made in alarm clocks of a familiar type.

The invention furthermore embodies cer-
 30 tain novel arrangements of parts and simple and economical features to accomplish the results herein stated, as well as other advan-
tages which will more fully appear from the following description when considered in connection with the accompanying drawings,
 35 in which:—

Fig. 1 shows in perspective an alarm clock embodying the features of the invention;

40 Figs. 1a, 1b, 1c, and 1d are sectional detail views on the lines a, b, c and d, respectively, Fig. 2;

Fig. 2 is an interior elevation of the same clock, looking from the rear with the back of the casing removed;

45 Fig. 3 is a plan view;

Fig. 4 is a view similar to Fig. 2, showing the parts in alarm sounding position;

50 Fig. 5 is a perspective view of a circular frame to support the alarm mechanism, and
 Fig. 6 is a perspective detail view showing

the improved slide members for effecting operation of the alarm upon the occurrence of a fire.

The casing 2 of the clock as shown in Fig. 1, is provided with a gong 4 which is secured to the clock casing 2 for the clock works. A clock mechanism is enclosed between the pair of plates, one of which, 5, appears in Figs. 2 and 4. Such mechanism includes the usual trains of time and alarm gears, with their actuating springs, and setting means for the time and alarm mechanisms. In connection with the latter, the hammer 6 is actuated by its spring to sound the alarm through the action of the usual pallet wheel 8 acting upon the pallet lever 9, the latter being connected through a link (not shown), to the hammer, and the pallet wheel being restrained against rotation ordinarily by a detent 10 carried by a spring arm 12, called the trip lever, and secured at one end to the front plate which encloses the clock works. The spring arm 12 ordinarily holds the detent in engagement with the teeth of the pallet 8 as shown in Fig. 2, but is withdrawn to thereby free the pallet and permit the alarm to strike when the time arrives for which the alarm mechanism is set to operate.

In order to ring the alarm intermittently the clock is equipped with the usual inter-
 80 mittent or repeat lever 14 having a latch 16 formed near its end which engages a projec-
tion 18 carried at the end portion of the pallet lever 9. The intermittent lever 14 is suit-
 85 ably fulcrumed between the plates 5 which enclose the clock works. The latch 16 is nor-
mally held in engagement with the projec-
tion 18 by a suitable spring (not shown), and the lever 14 is vibrated intermittently by a
 90 toothed wheel, to alternately engage and re-
lease the pallet 9, usually at intervals of about
thirty seconds, whereby the alarm is caused
to operate intermittently, or to repeat. In
order to permit a steady ringing of the alarm
 95 a finger piece 20 connected with a slide 21
which latter has a projection 22, is moved
to cause the projection to engage the outer ex-
tremity of the lever 14, and move the latter
 100 into a position where it is not permitted to in-
termittently engage and release the pallet 9.

On the left hand side of the clock, as viewed from Fig. 2, a finger piece 23 is connected with a slide 24 which carries a right-angularly projecting stop 25 which, as shown, may be moved into or out of obstructing relation to the hammer 6. When the finger piece 23 is moved so as to point to the word "Silent", the stop 25 engages the stem of the hammer 6 and prevents the latter from operating, but when the finger piece and its slide are moved so that the finger piece points to the word "Alarm", the stop 25 is removed from the hammer and the latter is free to operate. The foregoing features of operation and control are those which are common to alarm clocks of the type known as the Big Ben, and others. Applicant has modified the construction as contained in such clocks by the addition thereto of mechanism which will be caused to operate by an abnormal rise of temperature due to a fire. Such mechanism which applicant has so added, does not interfere with the normal functioning of the parts as are found in the clock as above described, but permits such functions to be performed without interference of the temperature controlling means which will be now described.

The circular frame 28 is inserted in the clock case and supports the slides 21, 24, 30 which are connected with the finger pieces 20, 23, and control the operations of the alarm, as above pointed out. The frame 28 is constructed with a flange 29, having therein openings 30 from which lead slots 31, the flanges 29 supporting the slides connected with the finger pieces, and the slots 31 permitting free operation thereof. The frame 28 supports two bar members 27, 27a, both 35 herein shown as sliding and located, respectively, upon opposite sides of the vertical center line of the clock as viewed from Fig. 2, said sliding members at their outer extremities having right angular bent portions 27b, 27c constituting projections or holding means 40 for a fusible connecting device.

The inner ends of the members 27, 27a, are pivotally connected to links 33, 34, whose opposite ends are connected through flexible members 32, 35, with spiral springs 36, 37, the 50 opposite ends of said springs being anchored as shown at 38 to a rigid portion of the clock frame at the bottom part thereof.

The outer extremities of the members 27, 27a, when the same are positioned as shown in Fig. 2, are brought together and connected by a fusible connection 40. As herein shown, this connection is in the form of a plate of metal or other material having a low melting point, carrying at its end portions two hollow nuts 41, which slip over the free ends 27b, 27c, and hold the parts in the position shown in Fig. 2, with the springs 36, 37 under tension.

I have herein illustrated the connection between the sliding member 27 and the finger piece 23 as consisting of a slot 42 in the slide

24 which engages a pin 43 on the link 33, thereby permitting relative motion between the slide 24 and member 27 and its link 33. Such connection permits independent adjustment of the stop 25 through the instrumentality of finger piece 23 to place said stop in obstructing position relative to the hammer 26, or out of such position, as determined by the words "Alarm" and "Silent". The other slidable member 27a, is shown as rigidly connected with the finger piece 20, whereby said parts would move together and without independence of movement. It is to be understood, however, that the slide 21 may be connected to the link 34 by a slot and pin connection, the same as herein shown for the slide 24 and link 33, so that the "Repeat" or "Steady" positions of the finger piece 20 may be made independently of the slide 21.

The slide 21 carries a cam 51 which is adapted when the slide is released to engage with the face of the spring arm 12 and move said arm laterally to thereby disengage the detent 10 from the teeth of the pallet wheel 8, and at the same time the projection 22 engages the end of the intermittent lever 14 and prevents the same from engaging the projection 18 on the pallet 9.

From the above description, it will be seen that when the sliding members 27, 27a are connected by the fusible plate 40, as shown in Fig. 2, the parts will be in such position that the alarm mechanism, comprising the usual alarm spring (not shown), the gear 45, and the train therefrom to the pallet wheel, will be free to operate the alarm at a predetermined time in accordance with the position of the alarm setting device, and without interference by the temperature alarm operating mechanism. That is to say, when the alarm spring has been properly wound and with the parts as shown in Fig. 2 of the drawings, the finger piece 23 is free to be moved for positioning the stop 25 into or out of obstructing relation to the hammer 26.

If out of such relation, when the time arrives for the alarm to sound, the detent 10 will be withdrawn, and the alarm sounded, and as shown herein, the device is organized so that an intermittent actuation of the gong will take place. If a fire should occur, thereby causing a rise of temperature sufficient to melt the fusible plate 40, the members 27, 27a will thereby be released and will be forcibly separated by the springs 36, 37. If the stop 25 happens to be in the position as shown in Fig. 2 where it will obstruct the movement of the hammer 6, the slide 24 will remove the stop from such position into that shown in Fig. 4. Movement of the member 27a will, through its slide 21 remove the detent 10 from the teeth of the pallet 8, and at the same time the projection 22 will engage the intermittent lever 14 so as to hold it out of position to interfere with the uninterrupted

vibration of the pallet lever 9, thereby permitting the gong to ring continuously.

As the improved parts of my clock are herein shown as organized, the gong will be caused to operate intermittently, or to repeat at intervals when the time controlled mechanism for the gong is operating in the usual way; while, on the other hand, if a fire should occur and cause the fusible member 40 to melt, thus releasing the temperature controlled gong actuating members 27, 27a, the intermittent action of the gong will be prevented and the gong will be made to sound continuously. With this organization of the parts, where the gong is set for example, to ring at six o'clock A. M., by a person who desires to be awakened at that time, if that person is awakened in the night for example, by the gong, and he notices that it rings continuously, he will instantly be apprised of the fire, as otherwise the gong would ring intermittently. This is a very useful function of my alarm apparatus in that the difference in the manner in which the alarm is sounded will warn a person of the existence of a fire, or of the fact that the alarm has been time actuated.

While I have herein shown a construction which desirably embodies the features of my invention, it is to be understood that the same may be varied within the reasonable limits, without departing from the spirit of the invention, provided such changes are within the scope of the following claims.

35 I claim:—

1. An alarm clock having in combination with the usual gong and time controlled striking mechanism, means for causing the gong to be actuated intermittently, only, under the time controlled mechanism, and automatic means for actuating the gong continuously, only, upon an abnormal rise of temperature.

2. In an alarm clock the combination with alarm mechanism including a gong, a striker and a train of wheels with means for causing the alarm to ring intermittently, only, at a predetermined time, of temperature actuated mechanism operating independently of the time actuated mechanism and constructed to cause continuous ringing of the alarm, only, upon the rise of temperature above a predetermined limit.

3. In an alarm clock, the combination of a gong, a striker and mechanism including time controlled devices for causing the alarm to ring, of temperature controlled means including oppositely sliding spring impelled members for ringing the alarm independently of the time controlled mechanism, and a fusible device for connecting said members.

4. In an alarm clock, the combination of time controlled alarm actuating mechanism, of temperature actuating mechanism operating independently of the time controlled mechanism and including two oppositely slid-

ing members, a fusible device connecting said members at one end, and spring devices connecting said members at their opposite ends.

5. In an alarm clock, the combination of a gong, a hammer, and time controlled mechanism for actuating said hammer, of temperature controlled devices for actuating the gong independently of the time controlled devices and including oppositely sliding members, a fusible device connecting the outer ends of said members, springs connecting the inner ends of said members, and a stop for obstructing the operation of the hammer connected with one of said sliding members.

6. In an alarm clock the combination of a gong, a hammer, and mechanism for effecting the actuation of the hammer for ringing the gong at a predetermined time, including a detent for engaging the usual pallet, said detent carried by a spring arm, two oppositely sliding spring controlled members arranged to be restrained from movement by a fusible link, a hammer obstructing stop carried by one of said members, and a cam carried by the other of said members and arranged to deflect the spring arm and remove the detent from the pallet, said members being caused to operate when said link melts upon a predetermined rise of temperature.

7. An alarm clock having, in combination, a gong, a hammer, and time controlled actuating mechanism for said hammer, a slide carrying a stop for obstructing the movements of the hammer, an adjustable finger piece connected with said slide, a second slide provided with a finger piece, a device for effecting intermittent or steady operation of the hammer to ring the gong, a finger piece for adjusting the position of said device, separately movable spring actuated slidable members connected, respectively, with said finger pieces, and a fusible device connecting said members and restraining their movements until a temperature sufficient to fuse said member has been reached.

8. An alarm clock having in combination time controlled alarm mechanism comprising a gong, a hammer and devices for actuating the hammer, oppositely sliding members, springs connected with said members and acting to separate them, a fusible device normally holding said members against separation, a hammer obstructing stop connected with one of said members, and means connected with the other of said members and arranged to release the time actuated mechanism and permit the alarm to ring when the temperature exceeds a predetermined limit.

9. An alarm independent of the time mechanism comprising a gong, a hammer and devices for actuating the hammer, oppositely sliding members, springs connected with said members and acting to separate them, a fusible device normally holding said members against separation, a hammer obstructing

stop connected with one of said members, and means connected with the other of said members and arranged to release mechanism and permit the alarm to ring when the temperature exceeds a predetermined limit.

10. In an alarm clock, the combination of a gong, a hammer, and time-controlled mechanism for actuating said hammer, of temperature controlled means for permitting actuation of the hammer by the hammer actuating mechanism independently of the time controlled devices, including two members one of which is slidable relatively to the other, a fusible device connecting said members, a spring connected with one of said members and acting to cause relative movement of the members when said fusible device melts, a cam carried by said member, and a spring having means for obstructing a rotating element instrumental in permitting movement of the hammer to strike the gong, said spring arranged to be deflected to release the striker mechanism when acted upon by said cam.

11. In an alarm clock, the combination of a gong, a hammer, and mechanism for effecting the actuation of the hammer for sounding the gong at a predetermined time, including a detent for engaging a rotary element of the hammer actuating mechanism, a spring arm carrying said detent, two projecting members, one of said members being slidable relatively to the other, a spring for acting upon said member to cause the separation of said members, a fusible device connecting said members, and a cam carried by said movable member and arranged to deflect the spring and remove said detent when said fusible device melts.

In testimony whereof I have hereunto set my hand this 3d day of July, A. D. 1931.

ROBERT O. FERGUSON.
